CLAIM

The ornamental design for a pan as shown and described.

DESCRIPTION

FIG. 1 is a front, top, left perspective view of the pan showing my new design;

FIG. 2 is a front elevational view thereof;

FIG. 3 is a rear elevational view thereof;

FIG. 4 is a left side elevational thereof;

FIG. 5 is a right side elevational thereof;

FIG. 6 is a top plan view thereof; and

FIG. 7 is a bottom plan view thereof; and,

FIG. 8 is an exploded view thereof.

(Continued)

The portions of the drawings illustrated in broken lines are directed to the environment and form no part of the claimed design.

1 Claim, 8 Drawing Sheets
